NECKTIE HOLDER

Hartman H. Knoebel, Jr., Elysburg, Pa.

Application March 22, 1937, Serial No. 132,393

1 Claim. (Cl. 24—56)

This invention relates to a necktie holder and has for the primary object the provision of an efficient and inexpensive device of this character which may be comfortably worn by a person and which will maintain a necktie in proper position relative to a collar and will prevent the necktie from slipping or loosening and thereby becoming disarranged.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a front elevation illustrating a holder constructed in accordance with the present invention and showing the same applied to a collar button of a collar of a shirt.

Figure 2 is a fragmentary sectional view showing the holder in applied position and supporting a necktie in proper relation to the collar.

Figure 3 is a perspective view illustrating the holder.

Referring in detail to the drawing, the numeral 1 indicates a plate in which is formed a slot 2 opening outwardly through one end of the plate and forming a portion of the plate with spaced tabs 3 adapted to straddle a shank 4 of a collar button 5. The collar button 5 is shown applied to a collar 6 of a shirt 7.

Integral with the plate 1 is a hook-shaped flange 8 located at one end of the plate and overlies the head of the collar button, as shown in Figure 2. Integral with the flange 8 and extending at substantially right angles thereto is an attaching ear 9 to which is secured a pin 11.

The plate 1 when adapted to the collar button, as shown, positions the pin 11 outwardly and downwardly with respect to the collar button, the pin projecting outwardly between the flaps of the collar so that it may be inserted in the knot portion of a necktie 12 to prevent the necktie from moving accidentally out of proper position with respect to the collar, also prevents the necktie from loosening or slipping consequently maintaining the necktie in its proper position.

Prior to tying the tie, the plate 1 is placed on the button with the pin 11 projecting outwardly between the flaps of the collar. The tie is then tied in the usual manner and adjusted properly on the wearer. The knot of the tie is then passed onto the pin 11, thereby retaining the tie in proper position and the pin also acting to prevent the tie from slipping or loosening.

What is claimed is:

A necktie holder, comprising, a pair of spaced legs fashioned together at the upper ends thereof to constitute a bridge having a folded section extending in parallelism with said legs, said folded section formed at the lower end thereof with a substantially right angular extending shelf, and a pin having the head section thereof secured in said shelf and the point section extending axially therefrom, said legs adapted to be inserted downwardly about the shank of a collar button between the head of said button and the outer face of a collar band whereby to position said folded section over the head of said button to maintain said shelf and pin in a position substantially coextensive with said shank for supporting a necktie in adjusted position on said pin when penetrated thereby.
